UNITED STATES PATENT OFFICE.

AUGUST ANDERSON, OF CHICAGO, ILLINOIS, ASSIGNOR TO AMERICAN CAR AND FOUNDRY COMPANY, OF ST. LOUIS, MISSOURI, A CORPORATION OF NEW JERSEY.

DOOR-LOCK FOR DUMP-CARS.

1,244,684.

Specification of Letters Patent. Patented Oct. 30, 1917.

Application filed April 5, 1915. Serial No. 19,221.

To all whom it may concern:

Be it known that I, AUGUST ANDERSON, residing at Chicago, Illinois, and being a citizen of the United States, have invented 5 certain new and useful Improvements in Door-Locks for Dump-Cars, of which the following is a full, clear, and exact description, such as will enable others skilled in the art to which it appertains to make and to 10 use the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings:

Figure 1 is a transverse sectional view of 20 somewhat more than half of the car width, is taken on line 1—1 of Fig. 2, and shows the door locking mechanism holding the doors in closed position.

Fig. 2 is a section of part of the car 25 through the central longitudinal plane thereof, and is taken on line 2—2 of Fig. 1.

Fig. 3 is an enlarged transverse sectional view, taken on line 3—3 of Fig. 2, and shows 30 a door locking mechanism similar to that of Fig. 1, but modified to accommodate flexible door raising means; and,

Fig. 4 is a horizontal section, taken on 35 line 4—4 of Fig. 3, illustrating the structure and disposition of certain of the parts as viewed in plan.

The present invention has been developed with a view to providing means for positively holding the doors of a dump car against accidental opening, but which will 40 permit a quick and positive release thereof at will without the imposition of undue shocks to the mechanism provided to accomplish these results.

Another object is to utilize the door-opening tendency of the load in the car to automatically oppose with equal strength any unintentional release of the doors. And the arrangement of the parts is such, that until a deliberate manipulation thereof has been 50 made, they are not in an operable relation to permit opening the doors.

A further object is to so form and apply to car center sills supporting members for

the door locking members, that a break down of the door supporting means is well 55 guarded against.

The mechanism occupies a highly protected position, where there is a minimum of danger of injury to it, and it is composed of 60 strong and substantial parts of simple character.

Whatever other advantages become apparent in the following disclosure are to be understood to be included within the scope 65 of the invention herein described.

In the drawings, 1 indicates the center sills or central supporting girder of a car, commercial channels with their flanges turned having been selected to serve as such, and 2 represents the side sills or bottom 70 chords of plate girder side walls 3, said sills being illustrated as angles with their horizontal legs outstanding, though any suitable structure may replace either of the adopted sills.

Attached to side sills 2 are hinge castings 4, which may, as shown, have flanges adapted to lie against the legs of the side sill angles and to be suitably secured thereto, and also having depending hinge lugs to which the 80 doors 5 may be pivotally connected.

The doors 5 are not restricted to any particular form, but preferably have depending side flanges and their inner edges stiffened by angles 6, the vertical legs of which form 85 a depending flange for that part of the door. In the closed position of the doors the inner edges thereof are adapted to bear against the under side of the center sills 1, and are held in tight contact with the latter 90 by locking dogs 7.

These locking dogs are arranged in pairs, and each pair constitutes a locking toggle, the dogs of each pair extending in opposite directions, and their outer ends are adapted 95 to pass beneath the vertical legs of stiffening angles 6 and to bear, when the doors are closed, against the bottom surfaces of bearing blocks 8, fitted into the internal angle of stiffeners 6, to the legs of which the said bearing blocks are secured. Blocks 8 may be economically produced in the form of castings.

Each locking dog 7 is hung through intermediate links 11 from a supporting casting or piece 9, which rests upon the upper 100

surface of the bottom flange of the center sill 1, and is secured to that flange and to the web of said sill. The supporting casting is provided with a depending lug 10, which extends through and below said center sill bottom flange, and from the lower end of each lug 10 is suspended the pair of links 11, one on each side of said lug. At their lower ends, each of said links is 10 pivotally connected to one of the locking dogs 7, intermediate its length.

The inner ends of said locking dogs are pivotally connected with each other and with an operating link 12 or 12^a, which 15 extends upwardly between the center sills 1, and when the doors are closed inclines toward one of said sills.

Operating link 12^a is different from link 12, in that it has intermediate its length a 20 loop 13, of such configuration as to permit a chain 14, of an affiliated door winding mechanism, to operate through said link without interference, or the link to operate without disturbing said chain.

25 At its upper ends, each operating link 12 and 12^a is pivotally connected with a crank arm 15, here shown as being of the bifurcated type, and each of said levers and its associated crank arm forms an operating 30 toggle for controlling the locking toggle. Said crank arms 15 are mounted upon and movable with an operating shaft 16, located between the center sills 1, at or near their tops, and to one side of the vertical 35 plane that is midway between the sills, which is also the central vertical longitudinal plane of the car. Operating shaft 16 may be of rectangular or other non-circular cross-section, and the hubs of said crank 40 arms have perforations of like contour, or said crank arms may be attached by keys, pins or cotters, etc., and may be operated by any suitable means (not shown).

Each crank arm 15 has an annular dis- 45 tancing and positioning flange 17 on its hub, the latter continuing beyond flange 17 to constitute a bushing 18, which is supported by and is revoluble in bearings 19. Annular flange 17 spaces the crank arm 15 a 50 suitable distance from the adjacent bearing 19, and prevents said crank arm changing its position to a point nearer said bearing.

Bearings 19 are preferably integral parts of certain of the shaft supporting castings 55 20, which are supported by the center sills, and may rest upon and be secured to the upper flanges thereof. All of the castings 20 are of the same formation, except that some may have the integral bearings just 60 referred to and, where the car is of the hopper type, the said castings are given a triangular contour to form supports for the longitudinal hood, usually present over the center sills.

65 To provide a suitable riveting area, the

cross-section of castings 20 has been shown as Z-shaped, though it may be angular, or, otherwise formed with this end in view. Castings 20 are recessed at 21 to allow pins 22, which connect operating links 12 and 12^a to their respective crank arms 15, to move unobstructedly when the parts assume the positions shown in dot and dash lines in Figs. 1 and 3.

Crank arms 15 are furnished with heels 75 23, each of which may be an integral extension from one of said crank arms, and which, when the doors are closed, bear against the under side of the top flange of a center sill 1, and so limits the movement 80 of the parts in the door-closing operation. And when the doors are closed, any tendency for them to open, as by reason of the weight of the lading, will be proportionately resisted by the reaction through locking dogs 7, operating links 12 and 12^a and members 15, whose heels 23 bear against the center sill flange, as set forth.

The *modus operandi* is as follows: With the doors closed, and the parts in the position shown in full lines, if it be desired to discharge a load, the operating shaft 16 will be rotated clockwise, as viewed in Figs. 1 and 3, until the crank arms 15 have moved, as indicated, into the recesses in the shaft 95 supporting castings 22.

The upper ends of operating links 12 and 12^a will also have been carried by the crank arms 15 to the same point, and the lower ends of said links, each pivoted to the inner ends of a pair of locking dogs 7, will rotate said dogs about their point of pivotal connection with supporting links 11.

Simultaneously links 11 will be caused by this same movement of operating links 12 and 12^a, to swing inwardly and upwardly, so that the locking dogs 7 will be given a combined rocking and swinging motion, which will result in their withdrawal, not only from under blocks 8 but out of the 100 way of the path of the doors 5, which will then drop to their open or discharge positions. The positions of the doors and of the parts of the door lock mechanism under these conditions is clearly indicated in dot 105 and dash lines in Fig. 1.

Doors 5 are raised to their closed positions by any suitable means, such as chain 110 14, but the raising means is not relied upon to lock and sustain them in place. After the closure of the doors, operating shaft 16 is rotated counter-clockwise, and crank arms 15 return to the position shown in full lines.

Responding to the action of the crank arms 15, operating links 12 and 12^a force the inner pivoted ends of locking dogs 7 downwardly from the positions shown in dot and dash lines in Fig. 1 to the full line positions in that figure. Locking dogs 7, during this action, have a reversed combined rocking 120

and swinging motion, and pass beneath their associated doors and bear against bearing blocks 8.

The last part of the downward thrust of 5 links 12 and 12^a cause the outer ends of the locking dogs 7 to press the inner edges of the doors in tight contact with the under side of the center sills 1. Each pair of locking dogs 7 constitutes a strong toggle, which 10 is now straightened out, and prevented from altering its position by another toggle, comprising one of operating links 12 or 12^a and the member 15, the heel 23 of the latter bearing against the top flange of one of the 15 center sills 1, and locking it against movement tending to release the doors by too great an action. There can be no unlocking of the doors until the crank arms 15 and operating links 12 and 12^a have passed, during 20 a reverse action, beyond the dead center line passing through the centers of operating shaft 16 and the pivotal connection of the pair of locking dogs. This can only be accomplished by the proper and deliberate 25 rotation of said operating shaft 16.

What I claim is:—

1. In a car door locking mechanism for oppositely disposed doors, a single locking toggle straightened to maintain the same 30 closed, and an operating toggle adapted to cause said locking toggle to support or release said doors.

2. In a single locking mechanism for car doors, a locking toggle comprising door-locking members adapted to be straightened to maintain a plurality of said doors closed, means for permitting the swinging of said locking members away from the doors, and mechanism adapted to rock said members 40 and cause the same to support or release said doors.

3. In a locking mechanism for drop doors, a locking toggle supported by oscillatory means and comprising door-locking dogs 45 adapted to swing away from said doors and being pivoted to and rocked by an operating toggle located between and supported by car center sills, and adapted to cause said locking toggle to support or release said 50 doors, and means for actuating said operating toggle.

4. In a car door locking mechanism for drop doors on opposite sides of car center sills, a plurality of locking toggles, one for 55 each pair of oppositely disposed doors, each toggle being supported from said sills by oscillatory means and comprising door-locking dogs, an operating toggle pivotally connected to each locking toggle and supported 60 from said sills and adapted to cause said locking dogs to support or release said doors, and means for simultaneously actuating all of said operating toggles.

5. In a car door locking mechanism, doors 65 hinged from car sides and adapted to close

against car center sills, a door-locking toggle comprising locking dogs, oscillatory links pivotally connected thereto intermediate their lengths, and supports attached to said center sills for pivotally suspending 70 said links from their centers of rotation.

6. In a car door locking mechanism, doors adapted to close against car center sills, a locking toggle having members supported from center sills by oscillatory means, and 75 an operating toggle comprising a link and a lever and an operating shaft to which said lever is attached.

7. In a car door locking mechanism, doors, car center sills against the bottom of which 80 said doors are adapted to close, supporting members connected with a lower portion of said sills, said members being sustained by the said sills, a plurality of depending oscillatory links pivoted to the lower portions 85 of said members, and locking dogs pivoted intermediate their lengths to said links and having their inner ends pivoted together, and operating means for said locking dogs.

8. In a car door operating mechanism, 90 center sills, doors having reinforced edges adapted to close against said center sills, bearing blocks secured to said edges, and a locking toggle comprising door locking dogs supported from said sills by oscillatory 95 means, and adapted to be rocked by operating means and to bear against said blocks to support the doors.

9. In a car door locking mechanism, rockable means adapted to engage doors to maintain them closed, a swinging support for said means and also an operating toggle therefor comprising a toggle-jointed link and lever, said lever being suitably supported, and a shaft for rotating said lever to cause the engagement and disengagement of the doors 100 by said rockable means.

10. In a car door locking mechanism adapted to coact with flexible door-raising means, rockable engaging means for doors, 110 an oscillatory support for said means, and an operating toggle therefor comprising a lever and a link.

11. In a car door locking mechanism, doors, car center sills against the bottom of 115 which said doors are adapted to close, said sills having flanges and webs, supporting members sustained by said sills, a plurality of oscillatory links pivoted to said members, locking dogs pivoted to said links and having their inner ends pivoted together, and operating means for said locking dogs.

12. In a car door operating mechanism, car center sills against the bottom of which 125 said doors are adapted to close, said sills having flanges and webs, supporting members sustained by said sills and positioned on the inner sides thereof, a plurality of oscillatory links pivoted to said members, locking dogs pivoted intermediate their 130

- lengths to said links and having their inner ends pivoted together, and means for operating said dogs.
13. In combination in a car, opposed doors closing near the center of the car, door lifting means, a single shaft extending longitudinally of the car and door locking latches having mutually responsive connection with each other and operable from said longitudinal shaft adapted to lock or release said opposed doors.
14. In a dump-car-door locking mechanism, oppositely extending rockable door-locking dogs, an operating toggle and means for actuating said toggle to cause said door-locking dogs to engage said doors.
15. In a car door locking mechanism, rockable locking means for a plurality of doors and operating means therefor, including a lever and a link depending from said lever and pivotally connected to portions of said door locking means that are associated with different doors.
16. In a dumping car, a central girder, a plurality of links depending therefrom, locking dogs connected with said links and a dog actuating member connected with said dogs.
17. In a dumping car, a central girder, a plurality of doors opening away from said girder, links depending from said girder, oppositely extending door locking dogs carried by said links adapted to extend beneath said doors and an operating means connected to both dogs adapted to rock the same.
18. In combination in a door locking means, a pair of oppositely extending and pivotally supported door locking dogs, in combination with a pair of oppositely opening doors, a rockable shaft and a member operable in response to the actuation of said shaft, pivotally connected with both said locking dogs and adapted to rock the locking dogs.
19. In combination in a door locking means, a central girder, a pair of dumping
- doors opening oppositely away from said girder, a pair of pivotally connected and oppositely extending door-locking dogs adapted to lock said doors in closed position and dog actuating means supported by said girder adapted to actuate said dogs.
20. In combination in a door locking means, a central girder, doors opening oppositely away from said girder, and means for locking both doors in closed position comprising an interconnected pair of oppositely extending door-locking dogs adapted to extend under said doors and means for simultaneously rocking both of said dogs.
21. In combination in a door locking means, doors adapted to open oppositely, a plurality of rockable door locking members adapted to underlie said doors when closed, a link connected with both said rockable locking members and rockable means adapted to cause said link to actuate said door locking members and thereby lock the doors in closed position.
22. In combination, a pair of pivotally connected oppositely extending door-locking dogs adapted to underlie a pair of oppositely opening doors of a dump car in combination with means pivotally supporting said locking dogs and means adapted to rock the same.
23. In combination in a dumping car, spaced center sills, side-supporting members, doors extending from said side-supporting members toward said center sills, rockable door-locking means including members adapted to engage oppositely extending doors and supported near said center sills and a shaft positioned above said door-engaging members and extending longitudinally of said sills and engaging said door-locking means.

In witness whereof I have hereunto set my hand in the presence of two witnesses.

AUGUST ANDERSON.
